UNITED STATES PATENT OFFICE

2,452,737

RESISTOR

Albert S. Eisenstein, Cambridge, and Kenneth J. Germeshausen, Newton Centre, Mass., assignors, by mesne assignments, to the United States of America as represented by the Secretary of War

Application March 21, 1944, Serial No. 527,498

2 Claims. (Cl. 201—63)

1

This invention relates to a resistor and particularly to a non-inductive type resistor adapted for use at high frequencies. The principal object of this invention is to provide resistance which will have negligible inductive reactance at high frequencies. This provision is desirable for such purposes as oscilloscopic study of wave forms. The resistance is embodied in a short section of coaxial line.

This invention contemplates current flow through an infinite number of radial resistance paths extending between the inner and outer conductors of a coaxial line so that contiguous magnetic fields associated with adjacent paths of current flow will oppose each other and tend to cancel.

In the drawing, Fig. 1 is a view, partly in section, of the invention, and Fig. 2 is a sectional view on the line 2—2 of Fig. 1.

Referring now to the drawing, the resistor is shown as a section of coaxial cable. The resistor has an outer sleeve 5, which may be internally threaded throughout its length for ease in manufacture. A resistance element 6 in any desired form such as a disc of a resistance compound as carbon or the like is exteriorly threaded for engagement with sleeve 5 and is disposed centrally within the sleeve. Resistance element 6 may assume any form so long as a resistance path radially from the inner conductor to the outer one is provided. Element 6 thus has its peripheral surface in conducting contact with an annular portion of sleeve 5. The resistance element may have any desired thickness along the sleeve axis. Resistance element 6 may also be in loose powdered form, if desired. End plugs 7 of insulating material are externally threaded for engagement with the sleeve and are disposed within the sleeve in abutting relationship to resistance element 6 on opposite sides thereof. Plugs 7 are provided with recesses 8 and 9 adapted to receive a spanner wrench for assembling the above-described members.

A solid metallic conductor 10 is disposed axially within sleeve 5 and supported in spaced relation to the sleeve by resistance element 6 and insulating plug 7. Conductor 10 has an annular portion of its surface in conducting contact with element 6. Conductor 10 may be rigidly secured in resistance element 6 if the latter is solid. The end of conductor 10 has an axial bore 11 to telescope the central conductor of an associated cable coupling.

Cable coupling construction is provided for each end of sleeve 5. This coupling construction,

2

which may be of conventional design, comprises coupling sleeve 15, threaded at one end for engagement with internal threads of resistor sleeve 5, and having an annular externally threaded flange 16 disposed about the sleeve inwardly of its other end. An insulating bead 17 disposed centrally within sleeve 15 rigidly supports a central conductor coupler 18 in spaced relation to the sleeve. Coupler 18 has end 19 reduced in section to telescope bore 11 of conductor 10, while the other end has an axial bore 20 to receive the central conductor of a coupled coaxial cable. The ends of conductor 10 may be suitably shaped to provide smooth surfaces for high frequency current flow at the junction points. A connecting coaxial cable may include solid central conductor 25 and woven metallic spaced outer conductor 26 maintained in any usual manner. A metallic ferrule 27, having an annular flange 28 at one end, encloses the end of outer conductor 26 and is rigidly joined thereto as, for example, by solder. Outer conductor 26 with its associated ferrule 27 fits snugly over the end of sleeve 15 and abuts annular flange 16. A ring nut 30, interiorly threaded for engagement with flange 16, has an inwardly extending annular flange 31, which engages flange 28 on the ferrule to lock the coupled coaxial cable to sleeve 15. Inner conductor 25 snugly telescopes axial bore 20 of coupler 18 to complete the coupling. In many instances the frequencies are low enough to use open wire in which case any suitable mode of connection to the resistor may be employed.

The enlarged sectional view, Fig. 2, shows a number of radial arrows 35, which represent the infinite paths of current flow through resistance element 6 between inner conductor 10 and outer conductor sleeve 5. Arrows 36 around the respective arrows 35 indicate diagrammatically the magnetic flux associated with each current path. It will be seen that contiguous circular paths of magnetic flux about adjacent radial current paths are opposite in direction, and hence adjacent fields will cancel. Consequently, there is no appreciable inductive reactance.

It will be noted that the distance between insulating spacer plugs 7 may be varied to meet requirements of high frequency transmission. So-called bead spacing formulae to reduce reflections are well known and may be used. Or resistor 6 may be thin enough so that plugs 7 may be considered as one unit for reflection purposes.

Having thus described the invention, what we claim as new and desire to secure by Letters Patent is:

1. A non-inductive resistance comprising an internally threaded outer metallic sleeve, an externally threaded annular resistance element disposed within said sleeve and in threaded engagement therewith, and a central conductor disposed axially within and in conducting contact with said sleeve and extending through said resistance element.

2. A non-inductive resistance comprising an outer metallic sleeve, an annular resistance element disposed centrally within said sleeve and having its peripheral surface in conducting contact with the inner surface of said sleeve, a central conductor disposed axially within and in conducting contact with said sleeve and extending through said resistance element, an insulating plug disposed about said conductor at each end of said element and in abutting relation to said element, the sleeve being internally threaded and

the resistance element and plugs being externally threaded and in threaded engagement with the sleeve.

ALBERT S. EISENSTEIN.
KENNETH J. GERMESHAUSEN.
